[57] **CLAIM**

The ornamental design for a wrench for installing and removing shotgun chokes, as shown and described.

DESCRIPTION

FIG. 1 is a top plan view of a wrench for installing and removing shotgun chokes showing my new design;

FIG. 2 is a perspective view thereof;

FIG. 3 is a left side elevational view thereof, which is a mirror image of the right side view;

FIG. 4 is a front elevational view thereof;

FIG. 5 is a rear elevational view thereof; and,

FIG. 6 is a bottom plan view thereof.
